FIG. 2

FIG. 1

FIG. 4

FIG. 3

FIG. 6

FIG. 5

FIGURE 1 is a perspective view of a pitcher showing my new design;

FIGURE 2 is a side elevational view;

FIGURE 3 is a front elevational view;

FIGURE 4 is a rear elevational view;

FIGURE 5 is a top plan view; and

FIGURE 6 is a bottom plan view.

A characteristic feature of my design resides in the angled dashed-line level indicia on the side walls and the full-line level indicia on the rear wall.

I claim:

The ornamental design for a pitcher, as shown and described.
